(57) **CLAIM**

The ornamental design for a sweat scraper and shedder for horses, as shown and described.

DESCRIPTION

FIG. 1 is a perspective view taken from the top and front side of a sweat scraper and shedder for horses showing my new design, the broken lines are for illustrative purposes only and forms no part of the claimed design;

FIG. 2 is a rear elevational view of the sweat scraper and shedder of FIG. 1;

FIG. 3 is a left side elevational view thereof;

FIG. 4 is a right side elevational view thereof;

FIG. 5 is a top plan view thereof; and,

FIG. 6 is a bottom plan view thereof.
